TRANSMISSION AND RECEPTION OF
INTELLIGENCE

Samuel G. Frantz and Brunson S. McCutchen,
Princeton, N. J., assignors to Radio Corpora-
tion of America, a corporation of Delaware

Original application April 23, 1935, Serial No.
17,775. Divided and this application April 17,
1963, Serial No. 74,834

7 Claims. (Cl. 179—1)

This invention relates generally to the transmission and reception of intelligence and is specifically directed towards improving the quality of the received intelligence.

5 The present application is a division of copending application Serial Number 17,775 filed April 23, 1935, entitled "Transmission and reception of intelligence" which in turn is a continuation in part of application Serial Number 496,595 now

10 U. S. Patent No. 2,006,989.

More specifically, the present invention relates to systems and methods for maintaining the relations between the various increments of the intelligence issuing from an electrical energy transmitting device at a receiving point substantially proportional to the relations between the various corresponding increments of the original intelligence.

An object of the invention is to provide a novel 20 and efficient method of transmission and reception of signals.

Another object of the present invention is the achieving of clear fidelity of reproduction at the receiving end of radio signals and in particular 25 music, by partial or total compression of the intensity range, or range of modulation at the transmitting end and corresponding expansion of the intensity range at the receiving end.

In the proposed system the degree or percentage 30 of modulation applied to the carrier wave at the transmitting end instead of being made directly proportional to the intensity of the signal in the microphone circuit is made to suffer a smaller percentage variation than the latter.

35 This may be called range compression or sub-proportional modulation. Thus, in this system a weak signal will be more amplified before it is used for modulation than will a strong signal. A feature of our invention is then that the intensity

40 range or the ratio between maximum and minimum percentage of modulation of the transmitted radio signal is less than the intensity range of the original signal. The extent or degree of this compression of intensity range may in practice 45 result in about the same ratio of maximum to minimum percentage of modulation as is at present obtained by manual control at broadcasting stations; or, the compression may be carried much further even to the limit at which there is

50 a total obliteration of intensity range and the signal is transmitted at constant percentage modulation. In general, in the present system the intensity range will be compressed but not obliterated.

55 At the receiving end of the present system

means are provided to re-expand the intensity range to that existing in the original signal. These means at the receiver must be so arranged as to work in correspondence with the compression effected at the transmission station. 5

At this point we desire to emphasize the fact that one of the benefits that will be derived from the use of our system will be the lessening of the effect of atmospheric disturbances upon the receiver. 10

The measure of the effect of atmospheric disturbances or other interference on the quality of reception is the ratio of interference intensity to signal intensity, and this effect will therefore be most pronounced when the signal intensity is 15 low. With the present system, during weak original signals, the transmitted signal intensity will always be greater than it would be were there no compression of intensity range before transmission, and therefore the effect of interference is 20 minimized. In other words, when weak signals are being transmitted the energy will be more amplified before it is used for modulation with the result that ordinary atmospheric disturbances will not obscure the signal. 25

This invention relates to and comprises the above described compression and expansion of intensity range, and means for accomplishing the compression and expansion. 30

In applicants' parent applications there are 30 proposed for this purpose three ways of informing the receiving apparatus as to what amount of expansion is necessary. The three cases may be classified as follows:

1. Separate wire or radio channel. 35
2. Variation of carrier frequency.
3. The use of the residual variation of modulation percentage itself as the signal which communicates to the receiving apparatus how much the signal should be amplified. 40

The simplest case of the latter would be logarithmic sub-proportional range compression at the transmitter with corresponding logarithmic super-proportional range expansion at the receiver. Expressed mathematically we have:— 45

$$\begin{aligned} I_2 &= k_1 I_1^a \\ I_3 &= k_2 I_2^a = k_1 k_2 I_1^a \end{aligned}$$

where I_1 =original intensity
 I_2 =transmitted intensity of modulation
 I_3 =receiver output intensity
 k_1 and k_2 are constants
 a and a =a constant <1 50

In using the system described in the third sub- 55

division it is obvious, of course, that the intensity range must not be completely obliterated.

An object of the present invention is to provide a specially constructed bridge arrangement for effecting the desired compression at the transmitter and expansion at the receiver.

Another object of the invention is the provision of a plurality of said specially constructed resistance bridges arranged in cascade.

10 Still other objects of the invention will be apparent from the following description of typical circuits according to our invention illustrated in the accompanying drawing, in which

Figure 1 illustrates a transmitter arrangement 15 of one form of our invention utilizing a so-called temperature bridge;

Figure 2 illustrates diagrammatically a method by which two or more temperature bridges may be cascaded; and,

20 Figure 3 illustrates diagrammatically a receiver in accordance with our invention employing a temperature bridge arrangement for receiving an appropriately expanding signal transmitted from a system such as shown in Figure 1.

25 Referring to Figure 1 a microphone circuit is shown composed of microphone 5, transformer 7 and the usual source of current 6. An amplifier for the current generated in the microphone circuit is shown generally at 8 coupled to the microphone circuit by means of the transformer 7. The output of the amplifier 8 is connected to a temperature bridge 9 by means of conductors 13 and 12 connected to diagonally opposite points 14 and 15 respectively of the bridge 9. The 30 other two diagonally opposite points of the bridge 9, namely, 16 and 17 are connected by conductors 11 and 10 respectively, to a modulator and radio frequency energy source circuit of any well known design. Referring more particularly to the temperature bridge 1, 2, 3 and 4 compose the four 35 elements thereof. Elements 1 and 4 are of the same material and elements 2 and 3 are of some other material having a different temperature coefficient of resistance than said first material.

40 The wires it will be evident are appreciably heated by the passage of the currents due to the signal voltage applied from the amplifier output. With maximum signal voltage the bridge is hottest and the resistances are so proportioned that 45 under this condition the bridge is almost balanced; that is, the ratio of bridge output voltage to bridge input voltage is a minimum. With very low input voltage the bridge is comparatively cold and has a maximum of unbalance and 50 hence the ratio of output to input voltage is a maximum. Thus the bridge acts as a non-proportional attenuator, attenuating strong signals more than weak ones. While we do not intend to limit ourselves to any particular construction 55 of the bridge one way in which the bridge could be constructed would be of small wires about the size of flash-light bulb filaments. Either 1 and 4 or 2 and 3 may be resistances so designed as to heat but little. Broadly, the 60 term "temperature bridge" as used herein includes any network with input and output connections in which the ratio of output to input voltage varies according to the input voltage 65 as a result of change of resistance of any of the elements of the network due to heating by the current passing through it.

In Figure 1 the arrangement could be such 70 that the elements 1 and 4 have comparatively high temperature coefficient of resistance and

elements 2 and 3 comparatively low temperature coefficient of resistance.

Attention is now directed to Figure 2. In said figure conductors 12 and 13 correspond to the conductors 12 and 13 leading from the output 5 of the amplifier 8 of Figure 1. Conductors 12 and 13 are connected to diagonally opposite points 21 and 20 respectively of the temperature bridge 18. The other two diagonally opposite points 22 and 23 of the bridge 18 are connected 10 by conductors 24 and 25 respectively to two diagonally opposite points 27 and 26 respectively of a second temperature bridge device 19. The other two points of said last named bridge, namely, 28 and 29 may be connected either to another similar bridge arrangement or to the modulator and radio frequency energy source as shown by Figure 1 through the medium of conductors 10 and 11. It will thus be evident that in the arrangement shown any number of temperature 15 bridges may be connected in cascade for obtaining any results desired.

Attention is now directed to Figure 3 which shows a receiver adapted to properly expand the signals which were compressed by the transmitter shown in Figure 1. In Figure 3, 30 represents generally a stage of audio frequency amplification in an ordinary radio receiver. Coupled to the output of said stage by means of transformer 31 is a temperature bridge 32 in accordance with our invention. It will be noted that the secondary of the transformer 31 is connected by conductors 33 and 45 to two diagonally opposite points of said bridge 32. The other two diagonally opposite points of the bridge 32 are connected by means of conductors 35 and 36 to the input of an amplifier generally shown at 37. The output of this amplifier 37 is connected by means of conductors 39 and 38 to a receiving instrument shown generally as a telephone receiver 40. The bridge 32 is made up of elements 1, 2, 3 and 4 which operate in a somewhat similar manner to that described above in connection with Figure 1 except that in the case of the receiver, the bridge will be in approximate balance 45 for minimum signal, so that in Figure 3 the greater the applied electromotive force across the secondary of the transformer 31 the greater will be the resistance of elements 1 and 4 compared to the resistance of elements 2 and 3. This 50 condition causes an increased unbalance of the bridge and an increased output current. It is to be distinctly understood that while we have shown only one bridge arrangement in the receiver shown in Figure 3 two or more such bridge arrangements may be arranged in cascade as 55 shown in Figure 2.

We claim:

1. In a radio receiving system including means for connecting the input of the system to a source of variable intensity signal energy and means for connecting the output of the system to a utilizing circuit, a four-arm resistance bridge interposed between said two means, opposite arms of said bridge being constructed so as to 60 have substantially the same temperature coefficient of resistance but one pair of said arms having different temperature coefficient of resistance than the other thereof, said bridge being adjusted so as to be approximately balanced 65 for minimum signal intensity and to become more and more unbalanced as the average intensity of the signal energy increases, the ratio of output to input voltage varying according to the input voltage as a result of change of resistance 70

- of any of the elements of the network due to heating by current passing therethrough.
2. In a radio communication system, a source of variable intensity signal voltage and a utilizing circuit, a four-arm resistance bridge, a pair of diagonally opposite terminals of said bridge comprising input terminals therefor, the other pair of diagonally opposite terminals of the bridge comprising output terminals therefor, means for connecting the source of signal voltage between the input terminals of the bridge and means connecting the utilizing circuit between the output terminals of the bridge, each of a pair of opposite arms of said bridge including means having a high temperature coefficient of resistance, the other pair of opposite arms including means having a comparatively low temperature coefficient of resistance, said bridge being adjusted so as to be approximately in a balanced condition for a predetermined value of average signal voltage and to become more and more unbalanced as the average intensity of the signal voltage departs from said value in one direction, the ratio of output to input voltage of said bridge circuit varying according to the average value of signal voltage as the result of change of resistance of any of the means provided in the arms of said resistance bridge due to heating by current passing therethrough.
3. In a radio communication system, a source of variable intensity signal energy and a utilizing circuit, a four-arm resistance bridge interposed between said source and the utilizing circuit, opposite arms of said bridge including means having substantially the same temperature coefficient of resistance but the means provided for one pair of said arms having different temperature coefficient of resistance than the other pair thereof, said bridge being adjusted so as to be approximately in a balanced condition for a predetermined average value of signal intensity and to become more and more unbalanced as the average intensity of the signal energy departs from said value, the ratio of output to input voltage of said bridge circuit varying according to the input voltage as the result of change of resistance of any of the elements of the network due to heating thereof by current passing therethrough.
4. In a radio communication system, a source of variable intensity signal energy and a utilizing circuit, a four-arm resistance bridge circuit interposed between said source and the utilizing circuit, opposite arms of said bridge including means having substantially the same temperature coefficient of resistance but the means provided for one pair of said arms having different temperature coefficient of resistance than the means provided for the other pair of arms, said bridge being adjusted so as to be approximately

in a balanced condition for substantially maximum average value of signal intensity and to become more and more unbalanced as the average intensity of the signal energy decreases, the ratio of output to input voltage of said bridge circuit varying according to the input voltage as the result of changes in the resistance of any of the elements of the bridge circuit due to heating thereof by current passing therethrough.

5. A volume range compressor comprising a resistance bridge having input terminals and output terminals, means for connecting a source of varying intensity voltage to said input terminals, a utilizing circuit connected to said output terminals, means connected in the arms of said bridge for attenuating electrical energy applied to the input terminals thereof to a greater or less extent depending upon the average intensity of the electrical energy applied to the input terminals of the bridge, said means attenuating high intensity energy to a greater extent than low intensity energy whereby the ratio between the lowest average intensity of the energy applied to the input of the bridge to the highest average intensity applied therat is substantially greater than the ratio of the lowest average intensity of the voltage appearing across the output terminals of the bridge to the highest average intensity voltage applied therat.

6. A volume range expander comprising a resistance bridge having input terminals and output terminals, means for connecting a source of varying intensity electrical energy to said input terminals, a utilizing circuit connected to said output terminals, said bridge including means for attenuating electrical energy applied to the input terminals thereof to a greater or less extent depending upon the average intensity of the electrical energy applied to the input terminals of the source, said means acting to attenuate high average intensity energy less than low average intensity energy, whereby the ratio between the lowest average intensity energy applied to the input terminals of the bridge and the highest average intensity applied therat is substantially smaller than the ratio of the lowest average intensity energy appearing across the output terminals of the bridge and the highest average intensity energy applied therat.

7. A volume range expander device comprising, a four-arm bridge circuit, substantially equal fixed resistance means having a low temperature coefficient of resistance connected in each of two opposite arms of the bridge and substantially similar resistance means having a high temperature coefficient of resistance connected in each of the other two opposite arms of the bridge.
